(57) **CLAIM**

The ornamental design for a rear light for a motor vehicle as shown and described.

DESCRIPTION

FIG. 1 is a front view of a rear light for a motor vehicle showing our new design;

FIG. 2 is a right side view thereof;

FIG. 3 is a top view thereof;

FIG. 4 is an enlarged view thereof, taken from area 4 in FIG. 1;

FIG. 5 is an enlarged view thereof, taken from area 5 in FIG. 2;

FIG. 6 is an enlarged view thereof, taken from area 6 in FIG. 3;

FIG. 7 is partially enlarged first perspective view thereof;

FIG. 8 is partially enlarged second perspective view thereof; and,

FIG. 9 is partially enlarged third perspective view thereof. The claimed design is shown in full contrast that indicates claimed areas. Half-tone shading indicates areas of unclaimed environmental structure. The dash-dash broken lines are included as boundary lines and form no part of the claimed design. The dash-dot broken lines indicating the boundaries of the enlarged views and the dash-dash broken lead lines, form no part of the claimed design.
